RESUSCITATOR

Philip L. Stanton, Pasadena, Calif.

Application October 27, 1958, Serial No. 53,171

Term of patent 14 years

(Cl. D83—1)

Fig. 1.

Fig. 2.

Fig. 4.

Fig. 3.

Fig. 5.

Fig. 1 is a front perspective view of a resuscitator showing my new design, the rear being substantially plain;

Fig. 2 is a front elevation thereof;

Fig. 3 is a right side elevational view thereof, the left side being substantially plain;

Fig. 4 is a top plan view thereof; and

Fig. 5 is a bottom plan view thereof.

The dominant feature of my design resides in the portion shown in full lines, the broken line representation of

a mask shown in Fig. 1, being omitted from Figs. 2, 3, 4, and 5 for convenience of illustration.

I claim:

The ornamental design for a resuscitator, as shown and described.
